(57) **CLAIM**

The ornamental design for a power strip, as shown and described.

DESCRIPTION

FIG. 1 is a perspective view of a power strip, showing our design;

FIG. 2 is a top view thereof;

FIG. 3 is a bottom view thereof;

FIG. 4 is a side view thereof;

FIG. 5 is an opposing side view thereof;

FIG. 6 is an end view thereof; and,

FIG. 7 is an opposing end view thereof.

The broken lines showing the environment are for illustrative purposes only.

The broken lines form no part of the claimed design.
